UNITED STATES PATENT OFFICE.

HARRY L. DUNCAN, OF MAHWAH, NEW JERSEY.

DIAPHRAGM.

Application filed April 2, 1919. Serial No. 286,958.

To all whom it may concern:

Be it known that I, HARRY L. DUNCAN, a citizen of the United States, and resident of Mahwah, county of Bergen, State of New Jersey, have made a certain new and useful Invention Relating to Diaphragms, of which the following is a specification taken in connection with the accompanying drawing.

- 10 This invention relates especially to diaphragms for acoustic instruments, such as phonographs, telephones, etc., in which the diaphragm is preferably formed of fibrous material, such as the desired number of 15 thicknesses of suitable cotton cloth, strong blotting paper, cotton batting, etc., carrying and preferably quite thoroughly impregnated with cured phenolic condensation cementing material, such as bakelite, 20 densite or Redmanol varnish compositions. Various parts of the diaphragm may be stiffened to the desired extent by forming corrugations or coned up or arched projections therein and at the same time the edge 25 portions of the diaphragm may be given a wavy or fluted form so as to secure a definite degree of peripheral elongation. Such a diaphragm when clamped or mounted so that this more or less irregular or wavy 30 edge is forced to a greater extent into flat or straight position is thereby placed under radial tension in its inner portions because this flattening tends to increase the edge diameter of the diaphragm. One or more 35 layers of such fabric or fibrous material may be united by the incorporated cured phenolic condensation cementing material so as to form an elastic rigid and strong diaphragm material which is especially ad- 40 vantageous for such tensioning wavy edge construction, since the desired definite peripheral elongation may be simply and effectively secured therein by pressure mold- 45 ing operations in suitable dies when the heat curing of the material is effected.
- In the accompanying drawing showing in a somewhat diagrammatic way a number of illustrative embodiments of this invention, 50 Fig. 1 is a side view of a diaphragm of this character partly in section.
- Fig. 2 is a diagrammatic sectional view showing the mounting of such a diaphragm; and
- 55 Figs. 3 to 7 are diagrammatic sectional views showing other forms of construction.
- Any suitable strong fibrous material may be used for diaphragms of this character in connection with suitable incorporated phenolic condensation cementing material, the 60 fibrous material for best results being such as is not undesirably affected by the cementing material or by the curing heat to which it is subjected which for rapid pressure molding and curing action is usually 65 about 300° to 320° Fahrenheit for fifteen to thirty minutes or so, although by using a longer time the curing heat may be considerably reduced. The fibrous material should also have sufficiently long fibre to 70 give the desired strength and coherence during the pressure curing or molding operation where considerable distortion of the previously formed sheet or blank of fibrous material occurs at this time and of course 75 longer fibre gives greater strength in the finished article, although the cementing action of the bakelite or other phenolic condensation cementing material naturally cures the fibres together and gives them greatly 80 increased strength under these conditions. For many purposes closely woven cotton fabric of which the threads are preferably of substantially uniform strength in each direction and in which the threads are pref- 85 erably loosely twisted is desirable for this purpose, the cotton threads under such conditions after the material has been impregnated so as to contain forty to sixty per cent more or less of dried bakelite varnish 90 No. 1, for example, yielding sufficiently under the heat curing treatment to permit considerable distortion so that the wavy edge portions or corrugated or other warped or 95 distorted portions of the diaphragm can be 100 reliably produced, and relatively constant shape, strength and other properties secured when the same number of thicknesses of similarly impregnated fabric are used in each case. As an illustrative example small phonograph diaphragms two or three inches in diameter may be conveniently formed of three or four layers of light muslin carrying about fifty per cent of cured bakelite 105 varnish and united under such high pressure curing conditions as above described so as to have a thickness of some six to twelve thousandths of an inch. Under some conditions, however, a smaller number of layers of thicker woven fabric, paper or 110 cotton batting may be used with quite good results. For larger diaphragms of six

inches or more in diameter heavier fabric or other material may, of course, be used or a greater number of layers of the lighter material may be employed, and in such cases a greater number of edge flutes may usually be employed to advantage for such radial tensioning purposes as compared to the relatively small diaphragms two or three inches in diameter where four to six flutes 10 more or less are more convenient and desirable for most purposes.

As indicated in Fig. 1 the diaphragm 1 may be formed of a number of layers of cotton or other suitable fabric carrying and 15 preferably thoroughly incorporated with such phenolic condensation cementing material as dried bakelite varnish compositions. Several layers of two ounce cotton fabric of this character carrying about fifty per cent 20 by weight of such cementing material may be assembled in a suitable mold and forced together under pressure of a number of hundred pounds per square inch, preferably in accurately shaped or equalizing molds preventing 25 excessive local pressures so that the fibrous material is not destroyed or distorted locally to an undesirable extent. During this heat curing and molding of the diaphragm 1 the edge portions 4 are preferably given a wavy or fluted form, three to six high spots such as 4 being formed therein with a corresponding number of intermediate low spots. A sinusoidal wavy form is desirable for this fluted or wavy edge which 30 may of course merge into the relatively flat portion of the diaphragm within at any suitable point, although it is not necessary in all cases for the wavy or transversely distorted portions to extend more than about 35 a third of the way to the center of the diaphragm. In some cases it is desirable to reinforce and strengthen this wavy edge portion by incorporating therewith additional impregnated fibrous material during 40 the heat curing and molding of the diaphragm and as shown in Fig. 1 an edge tensioning ring 5 may be used composed of additional thicknesses of impregnated cloth, paper or other fibrous material which may 45 be arranged on one or both sides of the other layers or interposed between them so that under the heat curing treatment they become securely cemented and united to the edge portions of the diaphragm sheets or 50 layers so as to proportionately strengthen this wavy tensioning edge portion.

When used such a diaphragm may advantageously be yieldingly clamped or mounted between any suitable form of elastic or yielding clamping supporting surfaces, such as 55 circular or flat sectioned rings or gaskets of vulcanized rubber, soft paper or the like, and Fig. 2 shows diagrammatically a suitable arrangement for this purpose in which 60 the clamping supporting means may com-

prise a rigid clamping ring or member 6 provided with a recess having an internal shoulder or flange 8 against which the rubber ring or yielding clamping member 9 may abut on its inner side, while at the same time sufficient free space is provided in the clamping means outside of this rubber ring, so that its free outward expansion can take place during the clamping of the diaphragm. The clamping members 6, 7 of brass or other suitable material may thus support the soft and yielding elastic vulcanized rubber clamping rings or members 9 which preferably have somewhat rounded contact surfaces for engagement with the diaphragm edge, such contact surfaces being advantageously located toward the outer edge of these yielding clamping rings or members so that the initial contact occurs at this point and a considerable radial tensioning may thus be secured on any diaphragm through the outward radial expansion of the clamping rings caused by their transverse compression, even aside from the radial tensioning secured by the flattening of the wavy edge portions of such a specially shaped diaphragm as described. In the mounting the elastic clamping rings or members may be forced together as by screws 10 so as to engage the diaphragm on each side throughout its entire periphery which is of course desirable and subsequent pressure yieldingly forces the wavy diaphragm edge into relatively flat position, thus tending to increase the diameter of this edge portion of the diaphragm and simultaneously exert radial tension on the inner portions which is desirable for many purposes because securing increased pitch and more reliable vibration in response to various impulses.

Fig. 3 shows another form of diaphragm in which not only the active vibrating portion is of substantially uniform thickness throughout, but in which the edge portion may also be of substantially the same thickness and such a diaphragm may be formed of the desired number of layers of such coated or impregnated cloth or other fabric or fibrous material. The different parts of the diaphragm may under such conditions be stiffened or strengthened by appropriately shaping them, the center 3 of this diaphragm 1 being coned up or projecting from the plane of the diaphragm body to a progressively increasing extent 110 which gives greatly increased stiffness thereto and promotes the vibration of this part of the diaphragm as a unit by minimizing local bending distortion thereof. A uniform thickness edge portion of a wavy character 115 may be advantageously formed on such a diaphragm. As indicated the high spots 12 may be sufficiently distorted as compared to the low spots 13 to secure a considerable definite increased peripheral length so as to 120 125 130

exert a desirable radial tensioning action when these wavy edge portions are flattened. For some purposes it is desirable to form any suitable transversely extending stiffened portion such as the integral stiffening rib or corrugation 11 between such a wavy edge portion and the inner portions of diaphragms of these types. Such a stiffener or rib may have sufficient stiffness transverse to the plane of the diaphragm to minimize or prevent undesirable buckling displacement of the parts within, which may be radially tensioned by the edge portions through the curved connections shown in connection with the rib. Such a diaphragm may be molded in suitable shaped molds under high pressure so as to compact the fibrous material and quite thoroughly shape it to the contour of the mold at the same time that the phenolic condensation cementing material is cured or solidified into its strong solid condition in which it gives such a high degree of resilient strength to the incorporated cotton or other suitable fibrous material.

Fig. 4 shows another form of diaphragm which may be advantageously produced from such fibrous material, the projecting stiffened center portion 3 being coned up gradually as indicated so as to project beyond the diaphragm body 1 and the edge portions may be given a tensioning action by forming three to six flutes or waves therein having high spots 15 and interposed low spots 14, the planes of which may be a sixteenth to an eighth of an inch or so apart in the case of relatively small diaphragms two or three inches in diameter. Fig. 5 shows another form of diaphragm which may be made of such material and have four to six or more edge flutes or wavy portions, such as 14, 15, connected with a suitably reenforced or stiffened diaphragm center of any desired character. If desired such a stiffened center may comprise a series of corrugations 17, 18, 19, the center 16 being flat, if desired, and stiffened in other ways under some conditions.

Fig. 6 shows still another form of diaphragm which may be advantageously formed of such fibrous material carrying or impregnated with cured phenolic condensation cementing material. The diaphragm may have fluted or wavy edge portions, if desired, and may comprise a series of high spots or portions 24 and correspondingly displaced intermediate low portions 26, and if desired also this wavy edge portion may be reenforced by an additional amount of similar impregnated fibrous material, such as the incorporated or united edge tensioning ring 25 which may have several times as great thickness as the inner portions of the diaphragm which may be of substantially uniform thickness, of say, five to ten

thousandths of an inch in small diaphragms, for example. This diaphragm may have a stiffened central portion comprising a series of corrugations which may be of such form as to bring the center portion 20 of approximately flat shape in some cases substantially into the plane of the edge portions as in the case of the Fig. 5 diaphragm. Additional corrugations 21, 22, 23 may be formed in some cases and a progressively increased stiffness may be secured in central portion by having these corrugations of substantially the same height or lateral extent on both sides of the central plane, while more or less conically inclined portions between corrugations or projections, such as 31, 32, 43 and 44 may be progressively flatter so as to more or less gradually approach the plane of the diaphragm outside which gives a desirable arrangement having a stiffening action which may approximate such a coned up shape as shown in Fig. 4, if desired.

Fig. 7 shows another form of diaphragm in which, if desired, the diaphragm center 33 may be coned up or stiffened and may have substantially the same thickness as the diaphragm body 34. In some cases it is desirable to unite or mold a metallic edge tensioning ring into such a diaphragm and for this purpose a flat or wavy tensioning ring 36 which preferably has a much greater radial width than its thickness may be united to the edge portions of the impregnated fibrous diaphragm material in any suitable way. These edge portions 35 of cloth or paper may in some cases be more or less brought around the metallic tensioning ring 36 so that the enclosing portions 37 are formed thereon which may be securely united to the diaphragm body 34 and to the tensioning ring during the pressure heat molding operation. If desired, however, the metallic edge tensioning ring may be interposed between the different layers of impregnated or coated fabric which may be forced around the ring during the heat molding so as to secure effective union between these parts. This molding operation may also in some cases serve to give the diaphragm edge portions a wavy or fluted contour similar to that of the tensioning ring, although the tensioning ring if not unduly stiff may be fluted at the same time that it is enclosed within or united to the fibrous diaphragm material. Such a metallic tensioning ring is desirable for relatively large diaphragms in some cases, although of course temperature expansion is much better equalized when the edge tensioning ring or portion is formed of practically or identically the same material as the inner portions or body of the diaphragm.

This invention has been disclosed in connection with a number of illustrative embodiments, forms, proportions, elements.

parts, shapes, materials, compositions, conditions, and methods of preparation, production and use, to the details of which disclosure the invention is not of course to be limited, since what is claimed as new and what is desired to be secured by Letters Patent is set forth in the appended claims.

1. The integral acoustic diaphragm, the central portion of said diaphragm being stiffened, the edge portions of said diaphragm being given a wavy form to secure increased peripheral elongation and a transversely extending intermediate stiffening member formed in said diaphragm adjacent its edge portion and joined to its central portion by a curved connection portion.
2. The integral acoustic diaphragm, the central portion of said diaphragm being stiffened, the edge portions of said diaphragm being given a wavy form to secure increased peripheral elongation and a transversely extending intermediate stiffening member having a portion extending substantially perpendicularly to the plane of the diaphragm and formed in said diaphragm adjacent its edge portion and joined to its central portion by a curved connection portion.
3. The acoustic diaphragm, the edge portions of said diaphragm being given a wavy form to secure increased peripheral elonga-

tion and a transversely extending intermediate stiffening member having a portion extending substantially perpendicularly to the plane of the diaphragm and formed in said diaphragm inside of and closely adjacent its edge portion.

4. The acoustic diaphragm, the edge portions of said diaphragm being given a wavy form to secure increased peripheral elongation and a transversely extending intermediate stiffening member formed in said diaphragm inside of and closely adjacent its edge portion.

5. The one piece acoustic diaphragm, the edge portions of said diaphragm being adapted to exert a radial tensioning action on the central portions and a transversely extending intermediate stiffening member formed in said diaphragm inside of and adjacent its edge portion, said stiffening member having a portion extending in a direction substantially perpendicular to the plane of the diaphragm.

6. The acoustic diaphragm, the edge portions of said diaphragm being adapted to exert a radial tensioning action on the central portions and a transversely extending intermediate stiffening member formed in said diaphragm inside of and adjacent its edge portion.

HARRY L. DUNCAN.
